UNITED STATES PATENT OFFICE.

WILLIAM WILEGUS, OF FORISTELL, MISSOURI.

POULTRY-WATERING DEVICE.

Application filed May 28, 1926. Serial No. 112,336.

This invention relates to poultry watering devices, and contemplates the use of a water container mounted for rotation upon a suitable trough, to maintain the latter supplied with water, the receptacle being provided with an outlet extension adapted to extend beneath the water level of the trough.

One of the chief characteristics of the invention resides in the provision of a novel construction of means for holding the water container against rotation in either of two positions, namely with the outlet extension arranged beneath the water level, or with said extension disposed to allow the container to be quickly and easily replenished with water as the occasion may require.

More specifically stated the invention comprehends the use of a sliding latch element adapted to engage one end of the water container to hold the latter against movement, the latch element being associated with resilient means, whereby the latch element can be effectively held in its active position, or conveniently released when it is desired to turn the water container upon its axis.

The nature and advantages of the invention will be better understood when the following detail description is read in connection with the accompanying drawing, the invention residing in the construction, combination and arrangement of parts as claimed.

In the drawings forming part of this application like numerals of reference indicate similar parts in the several views and wherein:

Figure 1 is a side elevation of the invention partly in section to show the outlet extension normally positioned beneath the water level of the trough.

Figure 2 is an end elevation partly in section, showing the active position of the container holding means in full lines, and its inactive position by dotted lines.

Referring to the drawing in detail 10 indicates a trough which may vary in size and configuration without departing from the inventive idea, although the end walls 11 are extended an appreciable distance above the upper edge of the trough as clearly illustrated, to provide bearings upon which the water container 12 is mounted for rotation. This container is provided with a centrally located shaft 13 which projects beyond the ends thereof and is journaled in suitable

openings in the end walls 11 of the trough. One of these openings 14 is in the nature of a slot to permit the water container to be quickly and conveniently removed from the trough for any purpose whatsoever. It will be noted that the opposed longitudinal edges of the trough 10, and the corresponding edges of the end walls 11 are rolled and receive a reinforcing frame 15 formed from a length of wire, to afford the structure the desired strength and rigidity, this frame including a substantially U-shaped portion 16 bearing against one end wall 11 and around the slot 14. The water container 12 at one end is provided with diametrically opposed notches 17 and 18 respectively and if desired these notches may be formed in a flange 19 projecting from the container. These notches are used in conjunction with a novel construction of means for holding the container against rotation in either of two positions, that shown in Figures 1 and 2, and in a position with the outlet extension of the container arranged uppermost to permit the container to be readily replenished with water as the occasion may require. The outlet extension is indicated at 20 and is normally arranged to extend beneath the water level of the trough 10, so that as the water is used from the trough, it is replenished from the container 12, the latter maintaining the water level of the trough more or less constant. Of course when it is necessary to refill the container 12, the latter must be turned upon its axis to arrange the extension 20 uppermost as will be readily understood.

The means for holding the container against rotation preferably consists of a sliding latch element 21 formed from a single length of wire or other suitable material, and slidable through openings in the parallel portions 22 of a substantially U-shaped bracket, the body portion 23 of which is suitably secured to the adjacent end wall 11 of the trough. One end of the latch element 21 is offset as at 24 in the direction of the receptacle and is adapted to be received by one or the other of the notches 17 and 18 above referred to, while the opposite end of the element 21 terminates to provide a hook-like portion 25 terminating to provide an extension 26.

The upper edge of the said end wall is rolled as at 27 to receive and support the limb 28 of a resilient element, the movable

limb 29 of which is connected with the limb 28 through the instrumentality of a resilient coil 30, the limb 29 being extended in the direction of the latch element 21 and adapted to be received by the hook-like portion 25 to hold the latter actively engaged with the container 12 for the purpose stated.

In practice, when the container is filled with water it is arranged with its extension 20 in the manner illustrated in Figures 1 and 2, in which position the offset extremity 24 of the latch element is received by the notches 17, and held positioned therein to prevent rotation of the container, by means of the movable limb 29 of the resilient element, which is arranged in the hook-like portion 25 of the latch element, such an arrangement being clearly illustrated by full lines in Figure 2. When it is necessary to refill the container with water, the thumb is arranged against the extension 26, and the finger engaged against the movable limb 29 of the resilient element, and by pushing on the latter it can be conveniently removed from the hook-like portion, during which operation the limb 28 turns within its bearings 27 as will be readily understood. After the latch element has been thus released, it can be turned on the bracket 23 and subsequently shifted to the left in an out of the way position, as illustrated by dotted lines in Figure 2, to allow the container to be turned upon its axis with a view of bringing the extension 20 uppermost, or in the position directly opposite that which it occupies in Figure 1, so that the container can be easily refilled. After the container has been thus arranged, the latch element 21 is positioned to arrange the offset extremity 24 thereof within the notch 18, which now occupies the position occupied by the notch 17 shown in Figure 2, and when the resilient element is associated with the latch element in the manner above described, the container is held immovable while being filled.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

1. In a device of the character described, a trough, a water container mounted thereon for rotation, and including an outlet exten-

sion projecting centrally from the container, a sliding latch element supported on one end of the trough and adapted to engage the container to hold the latter against rotation, and resilient means supported on the same end of the trough and adapted to engage the latch element to maintain the latter immovable in its active position.

2. The combination with a trough including end walls, and a water container journaled on said walls and having an outlet extension, of a latch element supported on one of the end walls and including an offset extension adapted to be received by a notch formed in said container, means for supporting the latch element for both sliding and turning movements, and resilient means supported on the same end wall of the trough and adapted to engage the latch element to hold it in its active position.

3. The combination with a trough having end walls, and a water container journaled on said walls and having spaced notches at one end thereof, and an outlet extension, of a latch element including an offset extremity adapted to be received by either of said notches to hold the container against rotation in either of two positions, means for supporting the latch element on one of said end walls for both turning and sliding movements, a hook-like extremity formed at the other end of said element, and resilient means mounted on the same end wall and cooperating with the hook-like portion to hold the latch element immovable in its active position.

4. The combination with a trough and a water container journaled thereon, and having diametrically opposed notches at one end thereof, of a latch element supported on one end of the trough for both sliding and turning movements, said element including an offset extremity adapted to be received by either notch to hold the container against movement in either of two positions, a hook-like extremity formed at the other end of said element, a resilient element including a limb journaled on the same end of the trough, and a resilient limb adapted to be received by the hook-like extremity of the latch element to hold the latter actively engaged with the container for the purpose specified.

In testimony whereof I affix my signature.

WILLIAM WILEGUS.
